UNITED STATES PATENT OFFICE.

JOHN P. BARRETT, OF CHICAGO, ILLINOIS.

MUNICIPAL LIGHTING AND POLICE SIGNALING SYSTEM.

1,065,653.

Specification of Letters Patent. Patented June 24, 1913.

Application filed July 12, 1911. Serial No. 638,073.

To all whom it may concern:

Be it known that I, JOHN P. BARRETT, a citizen of the United States, residing at Chicago, in the county of Cook and State of Illinois, have invented certain new and useful Improvements in Municipal Lighting and Police Signaling Systems, of which the following is a full, clear, concise, and exact description, reference being had to the accompanying drawings, forming a part of this specification.

My invention relates to the art of signaling and its object is to provide a system for summoning a police officer or watchman while he is out upon his beat.

To this end my invention contemplates a combined street lighting and police signaling system—in other words, the street lamps are used to signal the police, and my invention may thus be considered as an auxiliary system applicable to any ordinary or standard system of illumination.

The system of my invention is an electrical system and it is one of my important objects to provide an arrangement which will be an auxiliary unit, as far as possible, and which will be of universal adaptability, as far as possible. Thus, any municipality which maintains an electric system of street lighting may, by the use of my invention, utilize the street lamps for signaling purposes, the lighting circuits remaining substantially the same and the auxiliary circuits being merely added to or effectively associated therewith.

It is my object further to provide an auxiliary system, the use of which will not interfere with the standard requirements of fire underwriters and which is inexpensive to construct, which involves little wiring, and which is easily operated and maintained in proper condition.

It is well-known that, as a rule, particularly in the larger cities, the various districts or beats, which are assigned respectively to the various police officers or watchmen, are connected by telegraphic or telephonic communication with the police headquarters. In making his rounds, each police officer or watchman must communicate with the central office at predetermined intervals, in other words, must "pull the box," to make his reports and to register the fact that he is on duty. Between the visits to the district or beat telephone or telegraph instrument, or sending station, or "box," as it is

called, the police officer or watchman is likely to be anywhere in the district or on the beat and if the police headquarters wishes to communicate with him, however urgent the matter may be, there must be a delay until he makes his next visit to the box. Such delays are dangerous and, if it were always possible for the central police station to get the attention of the policeman on the beat, such prompt action might effectively interfere with the escape of a culprit. Thus, by flashing the street lamps, in accordance with my invention, the police officer or watchman on the beat may be apprised at any moment of the desire of the central office to communicate with him, and he may proceed quickly to the box and make the desired connection. The want of an arrangement of this kind has been felt in practically every municipality, but it is particularly emphasized in the case of large cities. Crimes and cases of misbehavior when reported to the central police, over the telephone for instance, may be taken care of by quick action, and this, in accordance with my invention, is secured by the central office signaling the particular district or beat from whence the report came, so that the officer may know that something has occurred within his reach which requires his attention.

In view of the fact that electric lighting circuits, such as are employed for street lighting, are often intricate and are varied, particularly in the matter of refinements which are controlled by the surrounding circumstances in each case, I make it a point to provide a system which is adapted to easily meet the various refinements and modifications and to meet the circuit ramifications which frequently result when a lighting system has been built up step by step during a number of years. It will be apparent to those skilled in the art that my invention is not necessarily limited to street lighting, although it is peculiarly adapted and related to such illumination, but that it could well be employed in connection with an interior system, particularly in large mercantile establishments where such a signaling arrangement might be found to be of special advantage.

The system of my invention requires the installation of a special switchboard and contact mechanisms at the distributing station and the employment of special mecha-

nism at the police station. The police station is connected with the distributing station by means of a cable comprising a number of conductors, and this constitutes the entire wiring except for some very simple wiring at the switchboard. So far as practicable, the operation is automatic. The attendant at the police station need only operate a selector key, so as to choose the proper police district, and then set the signaling mechanism for operation. The requirements of electric power companies and the fire underwriters are such that the lighting circuits themselves had best be controlled entirely at the distributing station, and the attendant there is drafted into service on these special occasions when a police signal is to be sent and he "sets up" the proper circuits. When the circuits are properly set, corresponding to the selection made by the police, the signaling mechanism is set into operation automatically and the lights are flashed, in accordance with a predetermined code if desired. In case it is desired to apply the signaling system of my invention to a lighting system already in use, it would be found only in rare instances that the lighting circuits and the police districts would be co-extensive and it, therefore, becomes necessary to provide special means for limiting the flashing of the lights to a particular area as closely as possible. It is possible that when it is desired to signal one district or beat, some of the lights in an adjacent district or beat might be flashed; this, however, is not only permissible, but might really be desirable and, while the lighting circuits might be slightly changed to avoid this being necessary, the inconvenience of such operation would not usually be enough to warrant the expense and trouble of changing the lighting circuits.

I have illustrated my invention diagrammatically in the accompanying drawings, in which—

Figure 1 is a view showing the general plan of my complete system; Fig. 2 is a more detailed representation of the operating parts at the distributing station and at the police station; and Fig. 3 is a detail view illustrating the relation between the targets and the switches associated therewith.

Referring first to Fig. 1, where a street lighting system is shown as an example, it will be seen that the lighted and protected area is divided into six so-called "police divisions." These divisions are marked off by the dotted lines and are numbered from 1 to 6 respectively. The central police station is indicated at P and one distributing station is shown at D. In order that every conceivable combination might be kept in mind, I have shown lighting circuits which are confined to one beat, lighting circuits which extend through more than one beat,

beats with more than one lighting circuit, and beats with lighting circuits from more than one distributing station. The other distributing station, which I have shown as a matter of example, is shown at D². The two distributing stations, so far as this invention is concerned, are substantial duplicates and the police station P is connected with each of them by means of a cable C. At the distributing station the electric generator A is provided, one terminal thereof being connected with the positive bus-bar 3 and the other being connected with the negative bus-bar 4. The ordinary switchboard is indicated at S, this switchboard having a double pole switch 5 for each of the line lighting circuits. One pair of terminals of each of the switches is connected across the bus-bars, in the ordinary manner, and the other terminals are connected across the line limbs. Thus, there are the line limbs a and b and the line limbs a¹, a², a³, and b¹. The line limbs a and b are connected directly across the switch terminals and, of the other lines, the limb b¹ is common, the other three being eventually connected together and to one of the last-named pair of terminals. Transformers T, T¹, T² and T³ are connected with the line limbs, the transformer T being connected across the line limbs a and b and the other three transformers being connected in parallel across the proper switch terminals of the left-hand switch 5. The local lighting circuits are shown at L, L¹, L² and L³. It will be noted that the lighting circuit L is the line by itself and that the other three circuits in effect are connected in parallel across the other line. There is an individual return for each of the lines L¹, L², L³, so that they can be individually controlled, as will be pointed out presently, although they finally do come together to make up the ordinary parallel arrangement. I have shown merely a representative lighting arrangement, and it will be apparent to those skilled in the art that other such arrangements might be used without departing from the scope and spirit of my invention. Each of the local lighting circuits comprises a number of serially connected arc lamps M, M.

At the distributing station the auxiliary switchboard W is provided. This auxiliary switchboard will be described in detail later although, as shown in Fig. 1, it will be seen that, broadly, it comprises a plurality of switches, each inserted in one side of a line so as to give auxiliary control for each local lighting circuit. Thus, the limb a¹ has the switch 6, the limb a² has the switch 7, the limb a³ has the switch 8, and the limb a has the switch 9. These switches are normally down upon contacts which are electrically united by means of jumpers 10, 10, and it will thus be seen that normally the

circuit is just the same as if no switches were present. It might be here pointed out that the switchboard W is only used on the special occasions, and that it would receive 5 and require no attention except at such times. The circuits are controlled in the ordinary manner at the panel S. It will be noted that the left-hand switch 5 of the panel S would control the local lighting circuits L¹, L² and L³ and the right-hand switch on this panel would control the lighting circuit L. These are the ordinary switches, which are turned on at nightfall to illuminate the streets in the ordinary way 10 and which are opened at the break of day. The distributing station D² has the line limbs a⁴, b², a⁵, a⁶, a⁷ and b³, to which are connected the transformers T⁴, T⁵, T⁶ and T⁷. These transformers feed the local lighting 15 circuits L⁴, L⁵, L⁶ and L⁷, and each of these lighting circuits comprises the serially connected arc lamps M⁴, M⁵.

Referring to Fig. 2, it is to be understood that the apparatus to the left of the left-hand dot-and-dash line is the special apparatus at the distributing station D. The apparatus between the middle dot-and-dash line and the right-hand dot-and-dash line is that at the central police station. The 20 lines extending between the dot-and-dash lines represent the cables which have been referred to.

The special or auxiliary switch panel W is illustrated more fully in Fig. 2 than in 25 Fig. 1. It will be seen that each of the switches 6, 7, 8 and 9, which are normally down upon the contacts 11, 11, connected together by the jumpers 10, 10, are pivoted on the posts 12, 12. The normally open 30 contacts 13 and 14 of each of the switches referred to are connected across the conductors 15 and 16 which, respectively, lead to the contacts 17 and 18 of the solenoid switch R. These contacts 17 and 18 are normally electrically united by the bridge-piece 40 45 19, which is carried upon a solenoid core 20 adapted to be drawn upwardly by the energization of the solenoid winding 21, which is connected in a circuit to be described 50 later.

Associated with the switches 6, 7, 8 and 9 are the indicating drops 22, 23, 24 and 25, respectively. These drops are merely indicated by rectangles upon the panel W, but 55 their broad nature is further illustrated above, where their circuit is also shown. It will be seen that they each comprise a winding 26, upon a core 27, an armature 28 pivoted at 29, a latch 30, a contact member 31 60 which the latch normally holds, and a target 32 which is normally out of view. When any of the windings 26 is energized the armature 28 is attracted, the latch 30 is raised, the circuit is broken at 31, and the target is 65 turned to view, as illustrated in dotted lines

in the drawing. All the windings 26 have their right-hand terminals connected together and to a common wire 33, which is connected with the positive pole of the battery B at the central station. Each of the 70 free terminals of the windings 26 are connected with one or more contacts 34, 34, which are associated with keys 35, 35 upon a keyboard K at the police station. These keys are all grounded together to the negative pole of the battery B. It will now be clear that each one of the switches 6, 7, 8, and 9 controls a local lighting circuit and that, when it is desired to signal a certain 75 district or beat, the local circuit or circuits which light that beat must be put under the special control. Thus, district No. 1 contains lights on local circuits L¹ and L²; district No. 2 contains lights on local circuits L¹ and L⁴; district No. 4 contains lights on local circuits L³ and L, etc. It will be noted 80 that the key 35, No. 1, has contacts which will close the circuits through relays 22 and 23. These relays correspond to switches 6 and 7, which in turn correspond to local light circuits L¹ and L². When the police headquarters wishes to signal district No. 1, key 35, No. 1, is depressed and drops 22 and 23 are energized. The corresponding targets drop and this is a signal to the attendant at the distributing station that the corresponding switches 6 and 7 should be thrown over so as to put the contacts 17 and 18 and the bridge 19 into the corresponding line limbs in lieu of the jumpers 10, 10. 90

For a reason which will be described presently, the drops should be restored when the switches are thrown over and I suggest the convenient arrangement shown in Fig. 3 whereby the handle of the switch may be used to kick the indicator upwardly so as to throw the contact piece into engagement with the latch. Since this switch panel W is in use only on special occasions, there will not be an attendant there all the time, of course, and I, therefore, provide a bell 36 in the common conductor 33, which is operated by the same current which operates any of the indicator drops. As soon as any of the keys at the police station is depressed, 100 the bell rings and the attendant immediately goes to the board to see which targets have dropped, and he will throw those switches to change the circuit and to restore the targets and the associated parts at the same 105 time. It is apparent that the different relations between the local light circuits and the police beats or districts are taken care of by the contact arrangement for the keys 35. Thus, every key which represents a 110 particular police district, has associated therewith a contact for a relay for every local lighting circuit included in that district, either wholly or in part. It is apparent, of course, that there may be a case 115 120 125 130

where one or two lights might be the only lights in that district on a certain local circuit and in such a case it might be desirable to omit control of those lights for that particular district in view of the many other lights which might be used to give the signal. However, it will be noted that any desired arrangement could easily be made by the simple wiring between the relays and the keyboard K. Taking district No. 2, for instance, it will be noticed that part of the lights in that district are fed from distributing station D and the others are fed from distributing station D²; thus for key 35, No. 2, we have two contacts, one going to the drop at station D which represents local circuit L¹ and the other leading to the drop at station D² which represents local lighting circuit L⁴. In each case each particular key controls the proper relays, which in turn give the indications as to the proper switches representing the light circuits which are to be flashed, as will be pointed out.

It is to be noted that, since the throwing of any of the switches 6, 7, 8 or 9 places the contacts 17 and 18 and the bridge 19 in the corresponding line limb in lieu of the permanent jumper 10, that the light circuit thus connected can be controlled by the solenoid switch R. In other words, each time that the winding 21 is energized, the circuit between the contacts 17 and 18 is broken and the lights will be flashed. This solenoid switch must have contact mechanism adapted to carry a heavy current, and in this respect I suggest the use of a solenoid switch. I provide mechanism at the police station which, when once set, automatically makes and breaks the circuit of this solenoid switch, such operation being desirable so that manual operation, with its danger of excessively rapid operation, may be avoided. Thus, at the police station, I provide a switch arm 37 which is pivoted upon a post 38 and which is adapted for electrical engagement with the contacts 39, 40 and 41 arranged circularly about the post 38. The switch arm 37 is held in its upper position, out of engagement with all the contacts, by means of a spring 42. When the switch arm is drawn down and then released it makes engagement with the three contacts successively and makes and breaks a circuit which will be described presently. In order to make and break the circuit three times it is necessary to draw the switch arm down all the way, but it is clear that if it is desired to make and break the circuit but once or twice, this can be accomplished by limiting the extent to which the switch arm is depressed. A dial or scale 43 is associated with the switch arm and stopping places are indicated thereon, for a purpose which will be described later.

The switch arm 37 carries a ratchet wheel

44 with which co-operates a pawl 45 mounted upon a spur gear 46 loosely mounted upon the shaft 38. This spur gear meshes with a pinion 47 which carries an escapement wheel 48 with it upon the shaft 49. A pallet 50, pivoted at 51, co-operates with this escapement wheel, this pallet being weighted at 52 so as to time the escapement mechanism.

The three contacts 39, 40 and 41 are connected together and, by means of a conductor 53, with one terminal of the solenoid winding 21. The terminal of this winding is connected with positive pole of the battery B'; by means of a conductor 54. The negative pole of the battery is connected with the switch arm 37 by means of the conductor 55, and it is now apparent that as the switch arm 37 makes engagement with contacts 39, 40, and 41, the circuit is closed through the solenoid winding 21 and the battery B'. This energizes the winding to lift the core 20, and consequently the bridge 19, and the circuit between the contacts 17 and 18 is broken.

I provide special mechanism which prevents operation of the automatic make and break mechanism until all the lighting circuits, to be flashed, are set up properly for operation. This mechanism is as follows: A catch lever 56, pivoted at 57, normally engages with the arm of the pallet 50. This catch lever is provided with an armature 58, which is associated with an electromagnet core 59 having the winding 60. This winding is connected in series with the battery B and all the contacts at the indicator drops. It will be seen that each of the contact arms 31 of the indicator drops has associated therewith a contact 61, and that the contact arrangements thus formed are connected in series by conductors 62, 62. The last of the series is connected with the common wire 33 which passes to the positive pole of the battery B. It will be understood here that the indicator drop contacts at both distributing stations are all in series and that the conductors 63 and 64 correspond to the conductors 33 and 65. In order that the circuit may not be closed through the battery B normally, this series circuit is broken between the switch spring 66 and the contact 67, the switch arm 37 having a button 68 which normally holds the spring off the contact. Thus, under normal conditions, although the circuit which includes the winding 60, and which may be conveniently referred to as the release circuit, is closed at all the indicator drop contacts in the entire system, it is open at the one point 66, 67. This, of course, is the normal position of the switch arm 37 and when it is drawn down the first circuit change that takes place is the closing of the circuit at the point 66, 67; it will be remembered, however, that at this time the attendant at the police station has

already depressed one of the keys 35 and that the circuit is broken at one or more places at the indicator drop contacts, so the winding 60 is not energized until all these contacts have been closed. As before described, these are all closed by the throwing of the required switches, so it will be seen that after all the circuits have been set up and everything is ready for the flashing, the 5 winding 60 will be energized and the armature 58 will be raised to move the catch lever 56 out of engagement with the arm on the pallet 50, and the escapement mechanism set free to operate. The escapement 10 mechanism is so timed that the arm 37 will rise slowly and so that the solenoid winding 21 is energized intermittently at the proper intervals. When the arm 37 resumes its 15 normal position the circuit through the release winding 60 is broken and the armature 58 may drop so as to throw the catch lever 56 back into the path of the arm on the pallet. This will prevent further operation of the escapement mechanism.

20 I shall now append a brief résumé of the entire operation of my system.

If the police headquarters desires to signal a certain district or beat, say for example District No. 2, the attendant at the 25 police station will momentarily depress key 35, No. 2. By reference to Fig. 1, it will be seen that beat No. 2 is lighted by local lighting circuit L^1 , fed from distributing station D, and local lighting circuit L^4 , fed from 30 distributing station D^2 . It will be seen that this key No. 2 has two contacts, one of which is connected with the proper indicator drop at distributing station D^2 and the other of which is connected with drop 22 at distributing 35 station D. Thus these two drops will be energized and the bell 36 will ring at both distributing stations, all by means of the current from battery B. At the same time that these drops are energized, the release 40 circuit is opened at these points. The attendant at distributing station D^2 , having his attention called to the special switchboard, will note that the relay corresponding to local lighting circuit L^4 has been actuated and will throw the corresponding switch. The attendant at distributing station D, having his attention called to the special switchboard at that station, will note that drop 22 has been actuated and he 45 will throw the corresponding switch. As the attendants throw up these switches, the targets are kicked back and the contacts, 31, 61 are closed so as to close the release circuit at these points. It is the attendant's 50 duty at the police station to pull down the lever 37 after he has pressed the proper selecting key 35. If he pulls down this lever before the attendants at the distributing stations have set up the circuits, the release 55 circuit remains unenergized and the switch

arm cannot go back upon its timed return. If he waits until after the circuits have been set up, the release circuit is energized just as soon as he starts to pull down the handle and will return immediately when he lets go. In either case, it is impossible to operate the make and break mechanism before the lighting circuits are ready to receive the action and there is always the effective reciprocal control between the distributing stations and the police station which insists upon proper operation. After the switch arm 37 has been drawn down and after the release circuit has been energized, the switch arm is free to travel back and makes and breaks the circuit through the solenoid winding 21. This device R can be operated with little current and so can the drop and release circuits, and there is little, if any, necessity for providing for sparking at the contacts. 70 As to the contacts 17, 18 and 19, which are adapted to carry a heavy current, there should be the usual consideration to take care of sparking. As the solenoid winding 21 is energized and deenergized, it makes and breaks the circuit in which its contact parts have been inserted, by the throwing of the switches, and it is apparent that the parallel relation shown on the board W in Fig. 2 provides means whereby any number 75 of circuits may be controlled at the same time. The conductors 54^a and 53^a, which proceed to the distributing station D^2 and have a solenoid winding 21 connected to them, are analogous to the conductors 54 and 53; this connects all the solenoid windings 21 in parallel and they will all operate under the present system. If it is deemed better practice to have but those which are intended to be effective operate, this may be accomplished by inserting multiple contacts electrically in each of the parallel circuits, placing these multiple contacts along the special switchboard under the mechanical control of the switches. 90

95 A code signal arrangement may be carried out by pulling down the switch lever 37, in accordance with the indications on the scale or dial 43, so as to make and break the circuit a different number of times for different occurrences. Different signals may convey different meanings to the police officer or watchman on the beat. It will be noted that when one of the switches 6, 7, 8 and 9 is thrown over there will be a momentary interruption in the lighting circuit. This may be desirable since it will attract the attention of the police officer primarily and, during the period which follows he may prepare to carefully observe the code. In other 100 words, the first flash would indicate that a code is to follow, while the other flashes would constitute the code itself. If desired, however, this preliminary interruption may be avoided by providing a switch which 105 110

makes one circuit before it closes another, and such an arrangement would be perfectly operative in the combination which I propose. It will be noted that the cables which connect the police station and the distributing stations need carry only low tension circuits and that an ordinary signaling current only need be employed. The high tension circuits are confined closely and properly to the switchboards.

It will be noted that the winding 60 is energized during the entire upward travel of the switch arm 37. When, however, the switch arm reaches the limit of its movement the button 68 engages the spring 66 and lifts it off the contact 67, thus opening the circuit and releasing the armature 58 so as to stop the escapement mechanism. This brings the entire apparatus back into normal position and into condition for another operation. At the distributing station a pilot lamp 69 may be provided in the release circuit. This will keep the attendant at the distributing station informed of the condition of the release circuit, since it will be lighted during the time that the switch arm is making its upward travel. When the switch arm reaches the upward limit of its travel and breaks the circuit, in other words when the signaling is completed, the pilot lamp is extinguished and the attendant may then throw back those of the switches 6, 7, 8 and 9 which have been actuated so as to restore the entire system to normal.

It will be clear to those skilled in the art that the arrangement herein shown and described might be enlarged and expanded without departing from the spirit and scope of my invention:

I claim as new and desire to secure by Letters Patent:

1. In combination, an electric power station, a plurality of circuits fed from said station, electric lamps in each of said circuits, a switch at said station for each circuit, an electric device for indicating each switch, circuits including said indicating devices, a second station, and selective switches at said second station for independently controlling said indicating circuits to designate which lamp circuit switch is to be operated.

2. In combination, a distributing station, a plurality of lighting circuits fed from said station, a switch at said station for each circuit, an electromagnet at each switch, means for selectively operating said electromagnets, a target and a switch contact controlled by each of said electromagnets, a loop adapted to be connected in any of said lighting circuits by its corresponding switch, make-and-break mechanism in said loop, contact mechanism for controlling said make-and-break mechanism, escapement controlled driving mechanism for said contact mechanism, means for normally preventing

operation of said driving mechanism, and a release magnet for said means in circuit with said switch contacts in series.

3. In combination, a distributing station, a plurality of lighting circuits fed from said station, a switch at said station for each circuit, an electromagnet at each switch, means for selectively operating said electromagnets, a target and a switch contact controlled by each of said electromagnets, a loop adapted to be connected in any of said lighting circuits by its corresponding switch, the throwing of such switches being adapted to return said targets and switch contacts to normal, make-and-break mechanism in said loop, contact mechanism for controlling said make-and-break mechanism, driving mechanism for said contact mechanism, means for normally preventing operation of said driving mechanism, a release magnet for said means inserted with said switch contacts in series, and a pilot lamp in said release circuit.

4. In combination, an electric power station, a plurality of circuits fed from said station, electric lamps in each of said circuits, a switch at said station for each circuit, an electric device for indicating each switch, circuits for said indicating devices, and means for selectively operating said devices to indicate which lamp circuit switch is to be operated.

5. In combination, an electric power station, a plurality of circuits fed from said station, electric lamps in each of said circuits, a switch at said station for each circuit, an alternative circuit part arranged to be looped into any of said circuits, make-and-break mechanism in said alternative circuit part, an electric device for indicating each switch, circuits for said indicating devices, and means for selectively operating said devices to indicate which lamp circuit switch is to be operated.

6. In combination, an electric power station, a plurality of circuits fed from said station, electric lamps in each of said circuits, a switch at said station for each circuit an alternative circuit part arranged to be looped into any of said circuits, make-and-break mechanism in said alternative circuit part, means for controlling said make-and-break mechanism, an electric device for indicating each switch, circuits for said indicating devices, and means for selectively operating said devices to indicate which lamp circuit switch is to be operated.

7. In combination, an electric power station, a plurality of circuits fed from said station, electric lamps in each of said circuits, a switch at said station for each circuit, an alternative circuit part arranged to be looped into any of said circuits, make-and-break mechanism in said alternative circuit part, means for controlling said

make-and-break mechanism, an electric indicator for each switch, circuits from said indicators, and means at said controlling means for selectively operating said indicators to indicate which lamp circuit is to be operated.

8. In combination, a distributing station, a plurality of lighting circuits fed from said station, a switch at said station for each circuit, an electro-magnet at each switch, means for selectively operating said electro-magnets, a target and a switch contact controlled by each of said electro-magnets, a loop adapted to be connected in any of said lighting circuits by its corresponding switch, make-and-break mechanism in said loop, contact mechanism for controlling said make-and-break mechanism, escapement controlled driving mechanism for said contact mechanism, means for normally preventing operation of said driving mechanism, a release magnet for said means in circuit with said switch contacts in series, and an audible signal in series with said electro-magnets, substantially as described.

9. In combination, a distributing station, a plurality of lighting circuits fed from said station, a switch at said station for each circuit, an electro-magnet at each switch, means for selectively operating said electro-magnets, a target and a switch contact controlled by each of said electro-magnets, a loop adapted to be connected in any of said

lighting circuits by its corresponding switch, make-and-break mechanism in said loop, contact mechanism for controlling said make-and-break mechanism, driving mechanism for said contact mechanism, means for preventing operation of said driving mechanism, and a release magnet for said means in circuit with said switch contacts.

10. In combination, a distributing station, a plurality of lighting circuits fed from said station, a switch at said station for each circuit, an electro-magnet at each switch, means for selectively operating said electro-magnets, targets controlled by said electro-magnets and a switch contact associated with each of said targets, a loop adapted to be connected in any of said lighting circuits by its corresponding switch, the throwing of said switches being adapted to return said targets, and switch contacts to normal, make-and-break mechanism in said loop, means for driving said make-and-break mechanism, means for preventing operation of said driving mechanism, and a release magnet for said means inserted with said switch contacts in series.

In witness whereof, I hereunto subscribe my name this 10th day of July, A. D., 1911.

JOHN P. BARRETT.
